ACCUMULATING APPARATUS

Edward A. Rockwell, Cleveland, Ohio, assignor to
The New Britain Machine Company, New
Britain, Conn., a corporation of Connecticut

Original application January 4, 1940, Serial No.
312,356. Divided and this application October
2, 1943, Serial No. 504,807

9 Claims. (Cl. 138—30)

1

My invention relates particularly to accumulators for accumulating fluid pressures, adapted to be used for applying pressures for any desired purpose, as for instance in connection with automobiles, airplanes, railway cars, mine locomotives, etc.

The object of my invention is to provide an accumulator applicable for any desired purpose in which fluid pressures may be accumulated in an advantageous manner. A further object is to provide an accumulator adapted to supply a hydraulic fluid under a constant pressure. Another object is to provide an accumulator which is charged up to a desired maximum previously by an intermittently acting pump, and so constructed as to maintain the hydraulic fluid under high pressures. Another object is to provide an accumulator of an improved form which is compact and which is provided with a spring-pressed accumulating means. Further objects of my invention will appear from the detailed description of the same hereinafter.

This application is a division of my application Ser. No. 312,356, filed January 4, 1940, now Patent No. 2,331,800, dated October 12, 1943, upon System for controlling the application of power.

While my invention is capable of embodiment in many different forms, for the purpose of illustration I have shown only one form thereof in the accompanying drawings, in which

Fig. 1 is a diagrammatic elevation of the accumulator shown as being associated with a supply reservoir, as well as with an intermittently acting electrically driven pump for charging the accumulator;

Figs. 2 and 3 together constitute a vertical section of the accumulator shown therein;

Fig. 4 is an end elevation of the same, and

Fig. 5 is a section taken on the line 4—4 of Fig. 2.

In accordance with my invention I have provided therein a reservoir gravity-feed tank 1 having a filler opening 2, an inlet 3 for the returned discharge liquid, which may be a hydraulic brake fluid or any other suitable liquid, and a removable cylindrical screen filter 4 located over an outlet or supply opening 5 which leads by a pipe 6, having a branch inlet pipe 6a for returned discharged liquid, to a rotary pump 7 which may, for example, be any desired type of gear pump. This is driven by an electric motor 8.

Pressure liquid is thus supplied from the pump 7 by a pipe 9 to an inlet 10 on a pressure accumulator 11. The pressure fluid from the pump 8 is thence received directly in a chamber 12 in

2

a cylinder 13 so as to force to the left in Figs. 2 and 3, a piston 14 which is mounted by means of a screw 15 on a plunger 16 between which piston 14 and plunger 16 there is a chevron packing 17, of suitable material. A snap ring stop 18 for the plunger 16 is located at the left of the cylinder 13, which latter is screw-threaded, and provided with a pair of ears 19 and 20, on the split end of said cylinder 13, secured together with a bolt 21, for screw-threaded attachment to a spring casing 22, so as to hold the screw-threaded end of the cylinder 13 fixedly on the spring casing 22. Also, above and opposite to the ears 19 and 20 there is a lug 22a having a bolt 22b therein for supporting an end of the accumulator from the automobile chassis in any desired way. The said plunger 16 rests against the face of a spring retainer plate 23. The spring casing 22 also has a split ring stop 24 for the retainer plate 23, which is also provided with an internal sleeve 25 to act as a guide for a plurality of Belleville spring washers 26 which are merely dished rings of spring steel. As shown in the drawings, the said rings 26 are located so that the adjacent rings have their dished portions extending in opposite directions, said rings being thus carried in an annular chamber 27 between the casing 22 and the guide 25 at intervals along the chamber 27. Between groups of the spring washers 26 there are ring-shaped blocks 28 to aid in maintaining the alignment of the spring washers 26. The left end of the chamber 27 is closed by a screw-threaded cap 29, having adjacent to a split end of the cap 29 a pair of ears 30 and 31, screw-threaded to the spring casing 22 and clamped together by a bolt 32, so as to hold the cap 29 tightly on the cylinder 22. Also, above and opposite to the ears 30 and 31 there is a lug 32a having a bolt 32b therein for supporting the end 40 of the accumulator from the automobile chassis in any desired way. Bolted to the left face of the cap 29 there is a cylindrical switch housing 34, which extends inwardly within the washer 26, the same having a removable screw-plug 35 to permit access to the switch terminals for leads 36 and 37 leading to the switch terminals. A cover plate 38 is bolted to the switch housing 34. In said cover plate 38 there is a sleeve 39 having a screw-threaded cap 40 to hold in place a sleeve 41 which has a screw 42 adapted to be received in a slot 43 in the sleeve 39. Said screw 42 also fastens in position an adjustable switch supporting rod 44 provided with a screw-threaded hole 45 to aid in the removal thereof. Slidably mounted on the rod 44 there is a copper plate 46 which

operates as a starting switch in the initial starting or setting of the switch apparatus, said plate 46 being normally held in its farthest position to the left by a light spring 47. The other end of said spring 47 abuts against a nut 48 on a sleeve 49 carried on the rod 44, said nut 48 having a washer 50 spacing it from an insulated ring 51 carried on the sleeve 49 and which supports two rod-shaped terminals 52 and 53 connected to said leads 37 and 36 respectively. The copper plate 46 is designed to initially close the circuit manually between the said two rods 52 and 53. The right-hand end of the rods 52 and 53 have screw-threaded thereto conducting plates 54 and 55 which are designed, in the automatic operation of the apparatus, to close the circuit with a copper disk 56 carried on a circuit-breaker sleeve 57 slidable within the sleeve 49 and normally held towards the right in Figs. 2 and 3 by a spring 58 to close the said circuit. It will be noted that the lead 36 is connected to one terminal 59 at one side of the motor 8 and the other lead 37 leads to any suitable source of electrical energy, as, for example, a battery, not shown, which latter is also connected by a lead 60 to a terminal 61 on said motor. The right-hand end of the rod 44 has a stop 62 cooperating with the interior of a shell 63 which is formed on the end of the circuit breaker sleeve 57. This shell 63 is adapted to be moved for the automatic making and breaking of the pumping circuit by a ring 64 mounted on a cylindrical member 65 carrying within the same a snap action circuit breaking member 66, the inner left portion of which rests against a spring housing 67, having a spring 68 within the same carried on the outside of a sleeve 69 which overlies a rod 70, having a headed screw 71 and a washer 71a supporting near one end thereof a washer 72 held in place by a snap ring 72a to retain said spring 68 in place.

The said snap action circuit breaking member 66 cooperates with two bell-crank levers 73 and 74 having rollers 75 and 76 thereon, which latter are forced against the face of the cylindrical member 65 by springs 77, resting against extensions 78 on arms of the bell-crank levers 73 and 74 which are carried by means of pivots 80. The arms 79 form a part of the switch housing 34. The rod 70, after passing through the snap action member 66, at the right thereof, carries a spring sleeve 81 having therein a spring 82 supported on a sleeve member 83 around the rod 70, which latter has a shoulder 84 supporting an end washer 85 to act as a retainer for said spring 82. The right-hand end of the rod 70 has a screw-thread 86 which is secured within the spring retainer plate 23 by means of nuts 87. Notches 88 in the face of the cylindrical member 65 also cooperate with said rollers 75 and 76 so as to retain the pump circuit broken when the pressure-liquid line is broken, that is to say when the piston 14 is at the extreme right-hand end of the cylinder 13. However, when the said liquid line is complete and the pump motor has been started manually by moving the copper plate 46 to the right, the pump will be started to supply the pressure liquid therefrom to the cylinder 12 and the piston 14 will move to the left, accordingly, until the snap action circuit breaker 66 breaks the circuit when the desired pressure has been accumulated, so that, thus, liquid is supplied from the cylinder 12 through a port 89 and thence through radial ports 90 in a check valve sleeve 91 which is normally kept in elevated position by means of a spring 92 carried in a cage 93 screw-

threaded into the end of the cylinder 13. The lower end of the cage 93 has a slotted opening 94 to permit removal thereof, the same being covered with a screw-threaded apertured dust cap 95. 5 Above the cage 93 there is a screw sleeve 95a, the adjusted position of the sleeve being maintained by a screw 96 cooperating with a series of slots 97 in said sleeve. This adjustment of the sleeve 95a also permits the tightening of an annular 10 seal 98 located above a washer 99, the seal 98 being supported on the other face thereof by a spacing member 100 which rests against an apertured sleeve 101 within which the valve member 91 slides. A check valve 102 is carried within 15 the valve member 91 and is held on its seat by a spring 103. The pressure liquid which is thus supplied by the force from the piston 14 is discharged past the check valve 102 and thence to a discharge port 104 leading to a pipe 105, this discharged pressure being a uniform pressure, preferably of about 500 lbs. per square inch. Another discharge pipe 106 conveys the pressure liquid at this same pressure from the discharge port 104 to any desired part to be moved, of an automobile or any other apparatus.

In the operation of the accumulator, it will be understood that the same is supplied from the supply reservoir 1 which conveys the liquid by the pipe 6 to the rotary pump 7, driven by the 30 electric motor 8. The liquid, placed under pressure by the pump 7, is delivered by the pipe 9 to the inlet 10 of the accumulator 11 so that any desired pressure is maintained thereby. Preferably, however, the accumulator is so constructed as to maintain a pressure, for example, of approximately 1000 lbs. per square inch. The liquid, under pressure, received in the inlet 10 from the pump 7 forces the piston 14 to the left, in Figs. 2 and 3, so as to place the spring washers 26 35 under compression. This continues until the circuit breaking member 66 passes beneath the rollers 75 and 76 so as to cause the cylindrical member 65 to move suddenly towards the left, thus causing the circuit breaker sleeve 57 to break the contact between the copper disk 56 and the conducting plates 54 and 55, so as to stop the motor 8 and the pump 7. This condition of the circuit, including the wires 36, 37, 59, 60 and 61, will continue until sufficient liquid has passed from the accumulator through the passageway 89, past the check valve 102 until the circuit breaking member 66 has been moved suddenly to the right-hand side of the rollers 75 and 76 so as to permit the spring 58 to again complete the motor circuit between the copper disk 56 and the conducting plates 54 and 55, whereupon the pump 7 will again charge the accumulator. In this way a constant pressure is maintained in the accumulator 11, irrespective of the extent of withdrawal of the liquid therefrom through the passageway 89. In the initial starting of the accumulator it will be understood that the copper plate 46 is arranged to be moved manually in opposition to the spring 47 in order to complete the circuit between the two rods 52 and 53. It will be understood, also, that the liquid which has been supplied under pressure from the pipes 105 and 106, after having been used or released from being under pressure, may return by the inlet 3 to the reservoir 1 or may be returned to the pump 7 by means of the pipe 6a.

While I have described my invention above in detail I wish it to be understood that many changes may be made therein without departing from the spirit of the same.

I claim:

1. An accumulator for a pressure fluid comprising, a movable wall adapted to be moved by the accumulation of a pressure fluid against the same, a series of dished members adapted to be compressed by the movement of said wall and when released to move said wall in the opposite direction so as to discharge said fluid under pressure, a tubular member attached to the wall around which the dished members are carried and an outer stationary tubular member in which the dished members are externally guided.

2. An accumulator for a pressure fluid comprising, a movable wall adapted to be moved by the accumulation of a pressure fluid against the same, a series of dished members adapted to be compressed by the movement of said wall and when released to move said wall in the opposite direction so as to discharge said fluid under pressure, a tubular member attached to the wall around which the dished members are carried, an outer stationary tubular member in which the dished members are guided, and means for maintaining the axial positions of the rings comprising a spacing ring guided between the said tubular members and located so as to separate the successive dished members.

3. An accumulator for a pressure fluid comprising, a movable wall adapted to be moved by the accumulation of a pressure fluid against the same, a series of dished members adapted to be compressed by the movement of said wall and when released to move said wall in the opposite direction so as to discharge said fluid under pressure, a tubular member attached to the wall around which the dished members are carried, an outer stationary tubular member in which the dished members are guided, and a stationary extension tube for receiving the dished members, connected to the outer tube and slideable in the inner tube.

4. An accumulator for a pressure fluid comprising, a movable wall adapted to be moved by the accumulation of a pressure fluid against the same, a series of dished members adapted to be compressed by the movement of said wall and when released to move said wall in the opposite direction so as to discharge said fluid under pressure, a tubular member attached to the wall around which the dished members are carried, an outer stationary tubular member in which the dished members are guided, a spacing ring guided between the said tubular members and located so as to separate the successive dished members, and a stationary extension tube for receiving the dished members, connected to the outer tube and slideable in the inner tube.

5. An accumulator for a pressure fluid comprising, a movable wall adapted to be moved by the accumulation of a pressure fluid against the same, a series of dished rings, normally dished

5 in opposite directions, adapted to be compressed by the movement of said wall and when released to move said wall in the opposite direction so as to discharge said fluid under pressure, and a stationary immovable spring casing against which the outside portions of said rings are guided.

6. An accumulator for a pressure fluid comprising, a slideable piston adapted to be moved by the accumulation of pressure fluid against the same, a series of dished rings, normally dished in opposite directions, adapted to be compressed by the movement of said slideable piston and when released to move said piston in the opposite direction so as to discharge said fluid under pressure, a stationary immovable spring casing against which the outside portions of said rings are guided, and a carrier for the dished rings associated with the slideable piston.

7. An accumulator for a pressure fluid comprising, a piston adapted to be moved by the accumulation of pressure fluid against the same, a series of dished rings, normally dished in opposite directions, adapted to be compressed by the movement of said piston and when released to move said piston in the opposite direction so as to discharge said fluid under pressure, a stationary immovable spring casing against which the outside portions of said rings are guided, and a plunger associated with said piston around which said rings are carried.

8. An accumulator for a pressure fluid comprising, a piston adapted to be moved by the accumulation of a pressure fluid against the same, a series of dished members, normally dished in opposite directions, adapted to be compressed by the movement of said piston and when released to move said piston in the opposite direction so as to discharge said fluid under pressure, a stationary immovable spring casing against which the outside portions of said members are guided, a plunger associated with said piston around which said members are carried, and spacing alignment members located between successive sets of members.

45 9. An accumulator for a pressure fluid comprising, a piston adapted to be moved by the accumulation of pressure fluid against the same, a series of dished rings, normally dished in opposite directions, adapted to be compressed by the movement of said piston and when released to move said piston in the opposite direction so as to discharge said fluid under pressure, a stationary immovable spring casing against which the outside portions of said members are guided, a plunger associated with said piston around which said rings are supported, and means for maintaining the axial positions of the rings comprising spacing alignment members located between successive sets of rings.
